UNITED STATES PATENT OFFICE.

WILLIAM M. WADLEIGH, OF MILKS GROVE, ILLINOIS.

WIRE FENCE.

SPECIFICATION forming part of Letters Patent No. 763,446, dated June 28, 1904.

Application filed May 2, 1903. Serial No. 155,277. (No model.)

To all whom it may concern:

Be it known that I, WILLIAM M. WADLEIGH, a citizen of the United States, residing in Milks Grove, in the county of Iroquois and 5 State of Illinois, have invented a new and useful Improvement in Wire Fences, of which the following is a specification.

My invention relates to woven-wire fences.

The object of my invention is to provide a 10 woven-wire fence of a strong, simple, efficient, and durable construction capable of being rapidly and cheaply manufactured, in which the line-wires may be independently tightened or adjusted, in which the fence may be 15 collapsed or narrowed in respect to its height or width for handling, shipment, or storage, which may be erected over sharp inclines, hills, or uneven ground without distortion or uneven strain, and in which the alternate line- 20 wires are loose and removable, and removably couple adjacent longitudinal sections of the fence together, so that by removing an alternate loose line-wire a section of the fence may be removed or an additional section added.

25 My invention consists in the means I employ to practically accomplish this object or result in a single unitary structure—that is to say, it consists in a woven-wire fence composed of a plurality of longitudinal strips or 30 sections loosely connected together by coupling line-wires and comprising in combination two sets or series of line-wires alternately arranged in respect to each other, one set carrying the diagonal mesh-wires and to 35 which the diagonal mesh-wires are rigidly and fixedly secured and each of which, in connection with the mesh-wires fixed thereto and carried thereby, constitutes in itself an independent longitudinal strip or section of the 40 fence and the other alternate set of line-wires being loose in respect to the diagonal mesh-wires and loosely coupling together the several longitudinal strips or sections of the fence, and a plurality of diagonal mesh-wires, each ex- 45 tending between two adjacent line-wires only and each having coils at intervals rigidly and fixedly securing the same to its line-wire and provided each with a series of angle-loops ex- 50 tends between its rigid or fixed coils to the adjacent alternate loose line-wire, over and

around which the loops extend. Each diagonal mesh-carrying line-wire (excepting the bottom and top ones) is furnished with two diagonal mesh-wires, the angle-loops of the one projecting upward to the adjacent loose 55 line-wire above and the angle-loops of the other projecting downward to the adjacent loose line-wire next below and the coils and angle-loops of the one mesh-wire alternating with those of the other. Each diagonal mesh- 60 carrying line-wire, with the diagonal mesh-wires fixed thereto, thus comprises a longitudinal section or strip of fence, which is removably coupled by the alternate loose or coupling line-wire to the next adjacent simi- 65 lar section or strip of fence. The angle-loops of the diagonal mesh-wires of adjacent strips or sections of the fence register with each other, so that when the fence is collapsed or narrowed the angle-loops of the adjacent 70 strips or sections will nest together. At the bend or fold of the angle-loops the mesh-wires may be provided with a loose coil loosely surrounding the loose or coupling line-wire when it is desired to prevent the diagonal mesh-car- 75rying line-wire being moved up or down independently of the loose or coupling line-wire, or vice versa. This may be of advantage at the lower portion of the fence, where the line-wires are placed close together to make a pig- 80 tight fence.

In the accompanying drawings, forming a part of this specification, Figure 1 is an elevation of a section of my improved fence. Fig. 2 is a section on line 2 2 of Fig. 1. Fig. 85 3 is a partial elevation showing the fence collapsed. Fig. 4 is a partial elevation enlarged; and Figs. 5 and 6 are sections on lines 5 5 and 6 6, respectively, of Fig. 4.

In said drawings, 10 10 represent the mesh-carrying line-wires, and 11 11 the alternate loose coupling line-wires.

12 12 are the diagonal mesh-wires, each having tight coils 13 at intervals about its diagonal mesh-carrying line-wire 10 and fixed 95 thereto and each provided with a series of angle-loops 18, extending to and loosely embracing the adjacent loose or coupling line-wire 11. The connection between the loose coupling-wire 11 and the angle-loops 12 con- 100

to its mesh-carrying line-wire, and provided each with a series of angle-loops extending between its tight fixed coils to the adjacent loose coupling line-wire about which the 5 loops extend, the intermediate mesh-carrying line-wire being furnished with two diagonal mesh-wires, the angle-loops of the one projecting upward and the angle-loops of the other projecting downward, substantially as 10 specified.

4. A woven-wire fence, comprising in combination a plurality of independent longitudinal strips or sections loosely coupled together by coupling line-wires, and each of said strips 15 or sections consisting of a mesh-carrying line-wire and a continuous diagonal mesh-wire secured thereto and carried thereby, and provided at intervals with a series of tight coils fixedly securing the same to said line-wire, 20 and furnished each with a series of angle-loops extending to and loosely embracing the adjacent coupling line-wire, and a plurality of loose coupling line-wires threaded through the angle-loops of adjacent longitudinal strips 25 or sections of the fence, substantially as specified.

5. A collapsible woven-wire fence, comprising in combination a plurality of independent longitudinal strips or sections, and a plurality 30 of loose coupling line-wires collapsibly connecting said strips or sections, each of said longitudinal strips or sections having a mesh-carrying line-wire and a continuous diagonal mesh-wire furnished with tight coils at intervals fixedly securing the same to its mesh-carrying line-wire, and with a series of angle-loops extending around and loosely embracing the adjacent coupling line-wire, the angle-loops of one section nesting with those of adjacent sections to collapse the fence, substantially as specified.

6. A collapsible woven-wire fence, comprising in combination a plurality of independent longitudinal strips or sections, and a plurality 45 of loose coupling line-wires collapsibly connecting said strips or sections, each of said strips or sections having a mesh-carrying line-

wire and a continuous diagonal mesh-wire furnished with coils at intervals fixedly securing the same to its mesh-carrying line-wire and 50 with a series of angle-loops extending around and loosely embracing the adjacent coupling line-wire, substantially as specified.

7. A collapsible woven-wire fence, comprising in combination a plurality of independent 55 longitudinal strips or sections, a plurality of loose coupling line-wires collapsibly connecting said strips or sections, each of said strips or sections having a mesh-carrying line-wire and a diagonal mesh-wire furnished with coils 60 at intervals fixedly securing the same to its mesh-carrying line-wire and with a series of angle-loops extending to and loosely embracing the adjacent coupling line-wire, and all of the mesh-carrying line-wires, excepting the 65 two marginal ones, having two diagonal mesh-wires fixed thereto with the angle-loops thereof projecting in opposite directions, substantially as specified.

8. A collapsible woven-wire fence, comprising in combination a plurality of independent longitudinal strips or sections, and a plurality of loose coupling line-wires collapsibly and foldably connecting said strips or sections, each of said longitudinal strips or sections 75 having a mesh-carrying line-wire and a continuous diagonal mesh-wire furnished with tight coils at intervals fixedly securing the same to its mesh-carrying line-wire, and with a series of angle-loops extending around and 80 loosely embracing the adjacent coupling line-wire, and all the mesh-carrying line-wires excepting the two marginal ones having each two diagonal mesh-wires fixed thereto with the angle-loops thereof projecting in opposite 85 directions, and the angle-loops of adjacent longitudinal strips or sections nesting with each other to collapse the fence, substantially as specified.

WILLIAM M. WADLEIGH.
